UNITED STATES PATENT OFFICE

120,552

DESIGN FOR A PORTABLE FIRE PUMP UNIT

Richard D. Kaul, Fairfield, Conn., assignor to
The Sealand Corporation, Bridgeport, Conn.,
a corporation of Connecticut

Application January 3, 1940, Serial No. 89,271

Term of patent 7 years

To all whom it may concern:

Be it known that I, Richard D. Kaul, a citizen of the United States, residing at Fairfield, county of Fairfield, State of Connecticut, have invented a new, original, and ornamental Design for a Portable Fire Pump Unit, of which the following is a specification, reference being had to the accompanying drawing, forming a part thereof, in which—

Figure 1 is a perspective view of a portable fire pump unit showing my new design, and
Figure 2 is a plan view.

I claim:

The ornamental design for a portable fire pump unit, as shown.

RICHARD D. KAUL.
